UNITED STATES PATENT OFFICE.

JOHN J. REYNOLDS, OF RANTOUL, ILLINOIS.

ANTIJOUNCE-SPRING CONSTRUCTION.

1,351,968.

Specification of Letters Patent. Patented Sept. 7, 1920.

Application filed February 15, 1918. Serial No. 217,343.

To all whom it may concern:

Be it known that I, JOHN J. REYNOLDS, a citizen of the United States, residing at Rantoul, in the county of Champaign and 5 State of Illinois, have invented certain new and useful Improvements in Antijounce-Spring Construction, of which the following is a specification.

The invention has for an object to effect 10 an improvement in the mounting of vehicle bodies upon the running gear and particularly to provide a spring adjustable to meet the requirements of various loads upon the same body. It is also a purpose to present a 15 mounting permitting the use of levers with springs engaged therewith to support the body, while at the same time retaining the advantages of three point suspension. It is an important advantage of the invention 20 that the body may be held in a fixed horizontal relation with respect to the axle although supporting levers are employed pivotally connected centrally of the body or adjacent the longitudinal medial axis of the 25 vehicle. It is a further advantage of the invention that adjustments for various loads may be quickly made without requiring special fastenings or locking devices while at the same time insuring the device against 30 casual disturbance of the adjustment.

Another advantage of the structure shown is that the vehicle body will be held securely 35 against lateral swing on the running gear; although lateral shocks to the running gear will be cushioned.

Further objects, advantages and features of invention will appear from the construction, arrangement and combination of parts hereinafter described and shown in the 40 drawings, wherein,

Figure 1 is a rear elevation of a vehicle mounted in accordance with my invention,

Fig. 2 is a front view thereof,

Fig. 3 is a sectional view on the line 3—3 45 of Fig. 1.

There is illustrated a vehicle including a body element 10 of any usual construction, a rear axle element 11, and a front axle 12. The rear axle 11 is provided with anchor 50 lugs 13, from which there depend swinging links 14 on each side of the axle 11. These links are connected to respective furcations 15 of the bifurcated lower ends of main body carrying levers 16. The levers 16 from the 55 opposite ends of the axle are crossed centrally over the axle, and pivotally connected

by means of a ball bearing joint 18 of a suitable form. The levers are extended beyond this joint, providing body arms 19 upon the outer ends of which the body 10 is supported. In the present instance the support consists of a leaf spring 20, disposed for flexure laterally of the body, the springs being secured at their upper heavy parts to suitable parts of the body frame, in the present 60 instance represented by standards 21. The springs curve slightly outward and the lever arms 19 have their end portions connected pivotally to the lower thin ends of the springs. The leaves of the springs are 65 preferably of a thickness and breadth to resist flexure in a direction longitudinally of the body 10, and are disposed to flex approximately in a vertical plane at right angles to the body. In the present embodiment of the invention, the rear axle element 70 11 is in the form of a housing for a live axle having a differential inclosed within an enlargement 22 of the housing at its central part. In order, therefore, to permit the 75 levers 16 full movement, they are each bowed upwardly at the middle of the vehicle, as at 23, the pivotal connection 18 between the levers being made intermediately of these 80 upwardly bowed portions. Intermediately 85 of the lengths of the lower parts of the levers 16, rearwardly projecting lugs 24 are formed, the outer end portions of which are continued vertically downward to form 90 spring anchorage arms 25, upon which there 95 are slidably anchor blocks 26, having at their inner sides suitable apertured lugs in which the outer ends of respective helical springs 27 are engaged, the inner ends of the springs being connected to respective 100 ends of a U-shaped yoke 28 having suitable form to hang in spaced relation to, and span, the differential housing 22 when the levers are at the uppermost limit of their movement and the springs 27 are adjusted at the 105 highest point upon the arms 25. By reason of the rearward extension of the lugs 24, the arms 25 are projected downwardly beside the levers 16 and slightly to the rear thereof, the ends of the arms extending a 110 suitable distance below the levers, and the upper part beginning a distance above the levers. The anchor blocks 26 are formed with interiorly threaded lugs 29 upon their outer sides, in which there are engaged respective screws 30 mounted revolubly in suitable ears 31 formed adjacent the bases

of the arms 25, the screws 30 being suitably held against longitudinal movement in the ears and having cranks 32 at their upper ends for operation.

5 The mounting of the body at the forward end is similar to that before described, with certain exceptions involving a difference in function and peculiar correlation between the two mountings having certain advantages of importance as will be readily understood. The axle 12 in this instance is formed with integral lugs 13^a, upon which links 14^a are hung, corresponding to those 14 before described, and furcated levers 16^a are connected at their lower ends to the links 14^a and centrally pivoted at their upper ends in the pivot casting 35, secured to the underside of the frame of the body 10, preferably by means of a suitable ball bearing, of which 10 a number of forms are available for such use. The levers 16^a are formed with downwardly extended spring anchorage arms 25^a, corresponding to those 25 before mentioned, between which a single spring 27^a is connected, by means of the anchor blocks 26^a 15 slidable upon the anchor arms.

Since the necessity for adjustment of the forward springs in certain types of cars will be negligible, owing to the fact that the 20 load is principally carried over the rear axle and the load carried by the front axle comprises principally the motor, driving mechanism, fuel supply, control, seat, and driver, the screw adjustment shown upon the rear mounting may be omitted.

In the present instance, one lever 16 is formed at its intermediate part 23 with parallel parts in each lever spaced sufficiently to receive the other therethrough, 25 the intermediate parts being suitably broadened to give them the necessary strength. At the rear side of the levers 16, lugs 40 are formed, between and to which a rebound check device 41 is mounted, preferably constructed in accordance with the details of my application Serial Number 167,422, filed May 9th, 1917. The lugs 40 may be extended rearwardly a sufficient distance to enable the device 41 to clear the differential 30 housing 22. The levers 16^a are provided on the rear side with lugs 42 between which a rebound check 43 is secured. The levers 16^a 35 may preferably consist of parallel bars located at the front and rear side of the axle 12, and the arms 25^a and spring 27^a may be duplicated with the necessary connections. It is thought that but one rebound check will be required, however.

It will be seen that by the construction 40 provided the front axle will have free move-

ment on the pivot of the levers 16^a at their upper ends, relatively to the body 10 when raised at either end, but the construction at the rear will hold the rear axle element approximately in parallel relation to the body 65 so that the latter is prevented from rocking objectionably. When the vehicle is to be used for carrying light loads, the screws 30 are manipulated to move the anchor blocks 26 toward the upper ends of the arms 25, 70 and when heavy loads are to be carried the adjustment is of an opposite character, so that greater resistance will be offered by the springs 27 to downward movement of the body. This adjustment may be quickly 75 made, as will be apparent and will be useful in obviating the necessity for providing such heavy springs upon the vehicle whereby it might be subjected to undue jar and vibrations when carrying light loads, in 80 order to have the maximum capacity for its heavier load. The mounting has the further advantage also of great flexibility in its support and the possibility of great strength at 85 the same time.

What is claimed:

1. In a vehicle, a body, a front and a rear axle, two support levers pivoted intermediate of the body over each axle and extending divergently downward, laterally 90 movable supports on each end of each axle connected to the outer ends of the respective levers constructed to permit considerable lateral movement of the levers with respect to the axle springs coengaged between the 95 levers of each axle, the levers adjacent one axle having respective upper extensions toward the sides of the vehicle opposite their lower ends and weight supporting connections between the said extensions and the 100 body; whereby the body may rock relatively to the said one axle, said body being pivotally supported directly upon the pivot of the levers adjacent the other of said axles fixed within certain limits with respect to 105 the horizontal.

2. In a vehicle, a body, an axle, pivotally connected levers having divergent lever parts connected to the axle for support and lateral movement thereon, and very stiff 110 leaf springs on the body extending and connected to parts on respective levers disposed in a direction not to yield to relative vertical movement between the body and levers.

In testimony whereof I have affixed my 115 signature in presence of two witnesses.

JOHN J. REYNOLDS.
